UNITED STATES PATENT OFFICE.

JAMES F. HOPPER, OF SHERMAN, TEXAS, ASSIGNOR OF ONE-HALF TO DANIEL K. PENN, OF SHERMAN, TEXAS.

GAS GENERATOR AND BURNER.

1,132,583.

Specification of Letters Patent. Patented Mar. 23, 1915.

Application filed December 11, 1914. Serial No. 876,630.

To all whom it may concern:

Be it known that I, JAMES F. HOPPER, a citizen of the United States, residing at Sherman, in the county of Grayson and 5 State of Texas, have invented certain new and useful Improvements in Gas Generators and Burners, of which the following is a specification.

My invention relates to a combined gas 10 generator and burner, and it particularly relates to a device of this character adapted to be used in connection with ordinary cooking and heating stoves, kitchen-ranges, &c., for burning kerosene oil, but also adapted 15 for other uses.

An object of the invention is to provide 20 a device of this character which may be fitted into the firebox and located above the grate of stoves of different sizes, or having different sized fireboxes, with equal efficiency.

Another object and essential characteristic 25 feature of the invention is to provide a device of this character having a return pipe extending from the gas generating coil to, and communicating with the top of the oil supply tank, into which tank any excess of 30 gas generated in the coil when in operation is conducted and it attains considerable pressure; causing a torch-like flame beneath the coil and thereby assisting combustion, giving the device a greater breadth of utility and adaptation.

A still further object is to provide a fuel 35 supply tank communicating with both the liquid supply pipe and the gas inlet pipe and having a novel arrangement insuring the filling of the tank only to a predetermined point, leaving space above the oil 40 for the receipt of gas when the burner is in use, and also, after the burner has first been used the supply of gas retained in the tank enables the burner readily started and heated when gas will again be generated.

45 Other objects and advantages will be hereinafter set forth and also to acquire a knowledge of the details of construction and means for effecting the results reference is to be had to the following description and drawings hereto attached.

In the accompanying drawings which are made a part of this specification, Figure 1, represents a front elevation of a stove with the burner applied and having a section

broken out through which the burner may be 55 seen, and Fig. 2 is a plan view of the same.

Referring more particularly to the drawings in which similar reference numerals designate corresponding parts throughout the several views, the different structural 60 features of the burner are preferably substantially as hereinafter described. However, they are susceptible to a greater or less degree of modification with reference to the spirit of the invention. 65

In the drawings, the numeral 1 indicates a stove of ordinary construction; 2 the usual fire box in which is located the gas generating pipes which comprise a combined horizontally disposed superheating coil 3, located at one end and near the top of the firebox; from the outer convolution of this coil a pipe 4 extends to near the opposite end of the box and is there connected by a transversely disposed loop 5 to a downwardly inclined pipe 6, that extends back to and through the end of the box and is connected by a laterally disposed pipe 7 to a burner pipe 8, that enters the box and extends centrally beneath the coil to near the opposite end of the box, and thence upward and back again through the box, to and connected near the top of an oil tank 9. Centrally located in the pipe 7 is a T, 10, provided with an angle valve 11 to which is connected an auxiliary burner pipe 12, closed at one end, that supplies gas to another burner supported thereby, when desired. From the inner convolution of the coil and connected in any usual manner to the bottom of the storage tank 9 is the oil supply or inlet pipe 13, provided with the usual controlling-valve 14, from which tank the supply of oil used with the present burner is taken. 70 75 80 85 90

The burner pipe 8 has a small perforation 95 or jet on the top side at 15 where the oil is ignited, and the pipe 12 has a similar jet at 16. 17 and 18 are draft tubes and mixing chambers, they are apertured at their base and vertically supported on the respective 100 pipes in any convenient manner. Perforations 19 are provided for the passage of air within the tubes. Secured to the generator pipe 8, by any proper means such as, for instance, eye bolts 20, are deflectors or spreaders 21, centrally located over the gas jets and adapted to spread the flame when the gas from the jets is burning. 105

The closed top of the oil tank 9 is perforated and provided with a tube 22, that extends down some distance within it, also a slight distance above the top of same, where it is closed by a cork 23; the tank is supplied with oil through this tube and its function is to prevent the tank being entirely filled with oil, thus insuring a chamber for gas when the burners are started. The pipe 8 is 10 forked before entering the tank and communicates with it at two points, 24 and 25; the former having an automatic check valve 26 entering in the tank, and the latter a throttle valve 27, for regulating the outlet 15 of gas as required.

In operation, liquid fuel passes from the supply tank through the supply pipe 13, and the quantity thereof is regulated by the valve 14; the oil continues its course through 20 the coil and other pipes and flows through the perforations 15 and ignited, thereby heating the coil and pipe sections to such an extent that the gas is quickly generated within the pipes, when the burning of the 25 gas from the jets keeps the coil and pipes continually hot enough to continue the generation of the gas so long as fuel is admitted through the pipe. After starting the first burner, should more heat be required, 30 the valve 11 may be opened and gas admitted to the jet 16, thus operating both burners. When more gas is generated than is consumed by the jets, it flows around and back through the pipes and enters the vacant portion 35 within the tank through the check valve 26, attaining desired density therein; and the same pressure being maintained in the pipes, exerts considerable force upon the burning jets; producing a torch-like flame 40 of intense heat, also a perfect combustion which thoroughly utilizes all of the heat

properties contained in the oil. When the operation of the burners is no longer required, the valves 14 and 27 are closed, when sufficient gas will be retained in the tank to again start them without the necessity of first flowing oil to the jets.

What I claim is:—

1. In a gas generator and burner for stoves and the like, a tank, an oil supply pipe 50 and generator pipes, the oil supply pipe connected with the bottom of the oil supply tank, and one of the generator pipes having a jet opening therein, and said generator pipe extended to the top of the tank and 55 connected thereto at two points forking therefrom, one of the said connections being provided with an inlet check valve, and the other with a throttle valve, for the purpose specified.

2. The combination with a stove of a gas generator and burner, an oil supply tank apertured through the top and provided with a tube extending some distance downward within it, and above the same to receive 60 a cork, a generating coil and generating pipes located within the firebox of said stove and an oil supply pipe opening in the bottom of the tank and extending to said coil, and said generating pipes communicating with 65 said coil and passing out of the box and to the top of the tank where it branches, entering the tank at two points; one of said branches being provided with a check valve and the other with a throttle, as and for the 70 purpose specified.

In testimony whereof I affix my signature in presence of two witnesses.

JAMES F. HOPPER.
